UNITED STATES PATENT OFFICE.

THOMAS F. MURPHY, OF UTICA, NEW YORK, ASSIGNOR OF ONE-THIRD TO JAMES F. COLLINS, OF UTICA, NEW YORK, AND ONE-THIRD TO CHARLES R. HUGHES, OF CHICAGO, ILLINOIS.

CIGARETTE HOLDER.

Application filed July 26, 1922. Serial No. 577,692.

To all whom it may concern:

Be it known that I, THOMAS F. MURPHY, a citizen of the United States, residing at Utica, in the county of Oneida and State of New York, have invented certain new and useful Improvements in Cigarette Holders, of which the following is a specification.

This invention relates to new and useful improvements in holders for cigarettes or 10 cigars.

One of the principal objects of the invention is to provide a holder with means for quickly releasing and positively ejecting the cigarette or cigar from the holder without 15 the necessity of any direct engagement of the cigarette or cigar by the user.

Another object of the invention is to provide such a holder with an ejecting means which subsequent to an initial manual ejecting movement will automatically increase 20 its rapidity of movement so as to impart a snap or sudden final ejecting movement to the cigarette, and thereby cause the cigarette to positively leave the holder, without any 25 other assistance from the user.

A further object of the invention is to provide such a holder and ejector with means for automatically stopping the outward or ejecting movement of the ejector 30 immediately upon performance by the latter of its function.

A still further object is to provide such a holder which is extremely simple in construction and is therefore cheap to manufacture.

In the drawings:

Figure 1 is a perspective view of a holder constructed in accordance with my invention.

Fig. 2 is an enlarged sectional view showing the preferred form of my invention, the cigarette clamp or ejector being shown in its normal or clamping position.

Fig. 3 is a similar view but showing the clamp or ejector at its extreme outward or ejecting position.

Fig. 4 is a perspective of the clamp or ejector in its closed or clamping position.

Fig. 5 is a detail sectional view showing a modified form of my invention, the clamp or ejector being shown in its normal or clamping position.

Fig. 6 is a similar view but showing the clamp or ejector at its extreme outward or 55 ejecting position.

Fig. 7 is a detail sectional view showing another modified form of my invention, the clamp or ejector being shown in its normal or clamping position; and

Fig. 8 is a similar view but showing the clamp or ejector at its extreme outward or ejecting position.

Referring to the accompanying drawings, 5 designates a mouthpiece for holding cigarettes or cigars and is formed with a 15 longitudinal bore 6 which terminates at its outer end in a counterbore 7.

Positioned within the counterbore 7 is a clamp A which normally clamps the cigarette to the mouthpiece, but which may be 20 shifted outwardly to eject the cigarette therefrom.

In the preferred embodiment of my invention, as illustrated in Figs. 1 to 4, this clamp is formed from spring sheet metal 25 and comprises a tube-like member. The inner end is formed with an inwardly extending flange 8 forming a consequent draft opening 9. The wall of the clamp adjacent the inner end is preferably formed with a 35 plurality of openings 10 and the outer end portion of the clamp is split longitudinally as shown by each numeral 11 to form resultant gripping fingers 12, the slots 11 preferably merging with the openings 10. The 45 exterior diameter of the inner end of the clamp is just a trifle smaller than the diameter of the counterbore, and the clamp tapers outwardly from the inner end to a 55 point 13. At the point 13, the metal of the 60 clamp is pressed outwardly at an angle of substantially 30° to form on its outer surface an inclined shoulder 14 and on its inner surface a seat 14a for the cigarette 15. The wall 65 of the clamp beyond the seat 14a lies substantially parallel with the wall of the counterbore and has frictional engagement therewith, and this wall terminates in a 70 radially extending flange 17. It will be understood that there is a flange 17 for each 75 gripping finger 12 and that these flanges 17 80 conjointly form an annulus, which annulus abuts the outer end of the mouthpiece and limits the inner movement of the clamp. This annulus furthermore projects beyond 85 the outer surface of the mouthpiece and serves as a means for manually engaging the clamp when it is desired to eject the cigarette therefrom.

In forming the clamp the fingers 12 are 90

95

100

105

110

normally spread radially and inasmuch as these fingers are resilient they will be compressed when the clamp is inserted within the counterbore and thereby surround and 5 clamp the inner end of the cigarette as shown in Fig. 2.

The inclined shoulder 14 is adapted to cooperate with the outer corner of the counterbore when the clamp is moved outwardly 10 during its ejecting movement.

When it is desired to eject the cigarette, the user engages the annulus 17 by his thumb and imparts an outward longitudinal movement to the clamp and immediately upon 15 the inclined shoulder 14 engaging the outer corner of the counterbore, the gripping fingers will begin to become relieved and their inherent resiliency will immediately cause them to expand radially. Due to the shoulder being at an angle of substantially 30° 20 the outward radial movement of the gripping fingers as well as the outward longitudinal movement of the clamp will be increased in rapidity relative to the initial 25 movement imparted to the clamp by the user, and as soon as the point 13 is reached (see Fig. 3) the radial movement of the fingers will cease and the outward longitudinal movement of the clamp will come to an 30 abrupt stop. Thus, the gripping fingers will be automatically freed from the cigarette and the abrupt stopping of the outward movement of the clamp will automatically thrust the cigarette bodily therefrom 35 without any further aid by the user. Inasmuch as the inner end portion of the tube tapers toward the inclined shoulder 14, the wall of said inner end portion will when the point 13 engages the outer corner of the 40 counterbore, expand and frictionally engage the inner surface of the counterbore, and thereby act as a further check against outward movement of the clamp.

It will therefore be seen that I have provided a clamp which is formed of a tube split longitudinally to form outwardly extending resilient gripping fingers which entirely surround the inner end of the cigarette and normally tend to open radially. 45 It will also be observed that the inclined shoulder cooperates with the mouthpiece whereby a short manually controlled initial movement of the clamp in an outward direction will be automatically followed by a further outward movement of increased rapidity to simultaneously release and thrust the cigarette bodily from the clamp. It will also be observed that the point 13 cooperates with the outer corner of the counterbore to 50 limit the outward movement of the clamp subsequent to the cigarette becoming freed from the gripping fingers.

In Figs. 5 to 8, I have shown two other forms for insuring the clamp against complete outward movement. In both forms 55

the clamp B has a non-tapering inner portion. The mouthpiece 5 in Figs. 5 and 6, is formed with an annular groove 18 adjacent its outer end which merges with the counterbore 7. A peripheral rib 19 is formed on the inner end portion of the clamp and is adapted to become seated in the groove 18 should the clamp pass beyond the inclined shoulder 20 during its outward longitudinal movement. 75

In Figs. 7 and 8, the groove 18 receives a split ring 21 which projects into the counterbore and is adapted to act as an abutment for the peripheral shoulder 22 formed on the inner end portion of the clamp and thereby prevent complete outward movement thereof. 80

I claim:

1. In a cigarette holder, the combination with a mouthpiece formed with a longitudinal bore and with a counterbore at its outer ends, of a clamp formed of spring metal for alternately holding and ejecting the cigarette and positioned in said counterbore for longitudinal movements therein, said clamp 85 being formed of a tube split longitudinally to form outwardly extending resilient gripping fingers entirely surrounding the inner end of the cigarette and normally tending to open radially whereby upon outward or 90 ejecting movement of the clamp relative to the counterbore the cigarette will be freed from the gripping fingers, and cooperating means between the fingers of the clamp and the mouthpiece for limiting outward movement of the clamp subsequent to the cigarette becoming freed from said gripping fingers. 95

2. In a cigarette holder, the combination with a mouthpiece formed with a longitudinal bore and with a counterbore at its outer end, of a clamp formed of spring metal for alternately holding and ejecting the cigarette and positioned in said counterbore for longitudinal movements therein, said clamp 105 being formed of a tube split longitudinally to form outwardly extending resilient gripping fingers entirely surrounding the inner end of the cigarette and normally tending to open radially whereby upon outward or 110 ejecting movement of the clamp relative to the counterbore the cigarette will be freed from the gripping fingers, said fingers being formed with flanges at their outer ends which conjointly form a continuous annulus 115 adapted to abut the outer end of the mouthpiece to limit the inward longitudinal movement of the clamp, and cooperating means between the fingers of the clamp and the mouthpiece for limiting outward movement 120 of the clamp subsequent to the cigarette becoming freed from said gripping fingers. 125

3. In a cigarette holder, the combination with a mouthpiece formed with a longitudinal bore and with a counterbore at its 130

outer end, of a clamp formed of spring metal for alternately holding and ejecting the cigarette and positioned in said counterbore for longitudinal movements therein, 5 said clamp being formed of a tube split longitudinally to form outwardly extending resilient gripping fingers entirely surrounding the inner end of the cigarette and normally tending to open radially whereby upon 10 outward or ejecting movement of the clamp relative to the counterbore the cigarette will be freed from the gripping fingers, said fingers being formed with flanges at their outer ends which conjointly form a continuous 15 annulus adapted to abut the outer end of the mouthpiece to limit the inward longitudinal movement of the clamp, said annulus projecting radially beyond the periphery of the mouthpiece to form means for manually 20 engaging and moving the clamp outwardly toward ejecting position, and cooperating means between the fingers of the clamp and the mouthpiece for limiting outward movement of the clamp subsequent to the cigarette 25 becoming freed from said gripping fingers.

4. In a cigarette holder, the combination with a mouthpiece formed with a longitudinal bore and with a counterbore at its outer end, of a clamp positioned in said counterbore for longitudinal movements therein for alternately holding and ejecting the cigarette, and cooperating means between the clamp and the mouthpiece whereby a short 30 manually controlled initial movement of the clamp in an outward direction will be automatically followed by a further outward movement of increased rapidity to simultaneously release and thrust the cigarette bodily from said clamp.

40 5. In a cigarette holder, the combination with a mouthpiece formed with a longitudinal bore and with a counterbore at its outer end, of a clamp positioned in said counterbore for longitudinal movements therein for alternately holding and ejecting the cigarette, and cooperating means between the clamp and the mouthpiece whereby a short 45 manually controlled initial movement of the clamp in an outward direction will be automatically followed by a further outward movement of increased rapidity to simultaneously release and thrust the cigarette bodily from said clamp, said means including a shoulder of substantially 30° 50 formed on said clamp for cooperation with the outer end of the mouthpiece.

60 6. In a cigarette holder, the combination with a mouthpiece formed with a longitudinal bore and with a counter bore at its outer end, of a clamp formed of spring metal for alternately holding and ejecting the cigarette and positioned in said counterbore for longitudinal movements therein, said clamp being formed into outwardly extending resilient gripping fingers for engag-

ing the inner end of the cigarette and normally tending to open radially, and cooperating means between said fingers and said mouthpiece whereby a short manually actuated initial movement of the clamp in an 70 outward direction will be automatically followed by a further outward movement of increased rapidity to simultaneously release and thrust the cigarette bodily from the 75 gripping fingers of the clamp.

7. In a cigarette holder, the combination with a mouthpiece formed with a longitudinal bore and with a counter bore at its outer end, of a clamp formed of spring metal for alternately holding and ejecting 80 the cigarette and positioned in said counterbore for longitudinal movements therein, said clamp being formed into outwardly extending resilient gripping fingers for engaging the inner end of the cigarette and normally tending to open radially, and a peripheral shoulder of substantially 30° 85 formed conjointly on said gripping fingers for engagement with the outer end of the counterbore whereby a short manually actuated initial movement of the clamp in an outward direction will be automatically followed by a further outward movement of increased rapidity to simultaneously release and thrust the cigarette bodily from the 90 gripping fingers of the clamp.

95 8. In a cigarette holder, the combination with a mouthpiece formed with a longitudinal bore and with a counterbore at its outer end, of a clamp formed of spring metal for alternately holding and ejecting the cigarette and positioned in said counterbore for longitudinal movements therein, said clamp being formed into outwardly extending resilient gripping fingers for engaging the inner end of the cigarette and normally tending to open radially, and cooperating means between the fingers of the clamp and the mouthpiece for limiting outward movement of the clamp subsequent to the cigarette becoming freed from said gripping fingers.

100 9. In a cigarette holder, the combination with a mouthpiece formed with a longitudinal bore and with a counterbore at its outer end, of a clamp formed of spring metal for alternately holding and ejecting the cigarette and positioned in said counterbore for longitudinal movements therein, said clamp being formed into outwardly extending resilient gripping fingers for engaging the inner end of the cigarette and normally tending to open radially, cooperating means between said fingers and said mouthpiece whereby a short manually actuated initial movement of the clamp in an outward direction will be automatically followed by a further outward movement of increased rapidity to simultaneously release and thrust the cigarette bodily from the gripping fin- 110 115 120 125 130

- gers of the clamp, and cooperating means between the fingers of the clamp and the mouthpiece for limiting outward movement of the clamp subsequent to the cigarette becoming freed from said gripping fingers.
10. In a cigarette holder, the combination with a mouthpiece formed with a longitudinal bore and with a counterbore at its outer end, of a clamp formed of spring metal for alternately holding and ejecting the cigarette and positioned in said counterbore for longitudinal movements therein, said clamp being formed into outwardly extending resilient gripping fingers for engaging the inner end of the cigarette and normally tending to open radially, a peripheral shoulder of substantially 30° formed conjointly on said gripping fingers for engagement with the outer end of the counterbore whereby a short manually actuated initial movement of the clamp in an outward direction will be automatically followed by a further outward movement of increased rapidity to simultaneously release and thrust the cigarette bodily from the gripping fingers of the clamp.
15. In a cigarette holder, the combination of a mouthpiece formed with a bore and with a counterbore at its outer end, and a clamp positioned in said counterbore for longitudinal movements therein for alternately holding and ejecting the cigarette, said clamp being formed of a spring metal tube split longitudinally to form outwardly extending resilient gripping fingers normally tending to open radially, the outer end portion of the tube being flared to form a seat for the inner end of the cigarette and an exterior inclined shoulder adapted to cooperate with the outer end of the mouthpiece whereby a short manually controlled initial movement of the clamp in an outward direction will be automatically followed by a further outward movement of increased rapidity to simultaneously release and thrust the cigarette bodily from the clamp.
20. In a cigarette holder, the combination of a mouthpiece formed with a bore and with a counterbore at its outer end, and a clamp positioned in said counterbore for longitudinal movements therein for alternately holding and ejecting the cigarette, said clamp being formed of a spring metal tube split longitudinally to form outwardly extending resilient gripping fingers normally tending to open radially, the outer end portion of the tube being flared to form a seat for the inner end of the cigarette and an exterior inclined shoulder adapted to cooperate with the outer end of the mouthpiece whereby a short manually controlled initial movement of the clamp in an outward direction will be automatically followed by a further outward movement of increased rapidity to simultaneously release and thrust the cigarette bodily from the clamp.
25. In a cigarette holder, the combination of a mouthpiece formed with a bore and with a counterbore at its outer end, and a clamp positioned in said counterbore for longitudinal movements therein for alternately holding and ejecting the cigarette, said clamp becoming freed from said gripping fingers, said fingers being formed with flanges at their outer ends which conjointly form a continuous annulus adapted to abut the outer end of the mouthpiece to limit the inward longitudinal movement of the clamp, said annulus projecting radially beyond the periphery of the mouthpiece to form means for manually engaging and moving the clamp outwardly toward ejecting position.
30. In a cigarette holder, the combination with a mouthpiece formed with a longitudinal bore and with a counterbore at its outer end, of a clamp for alternately holding and ejecting the cigarette formed of spring metal and positioned in said counterbore for longitudinal movements therein, said clamp being formed of a tube split longitudinally to form outwardly extending resilient gripping fingers entirely surrounding the inner end of the cigarette and normally tending to open radially whereby upon outward or ejecting movement of the clamp relative to the counterbore the cigarette will be free from the gripping fingers, cooperating means between the fingers of the clamp and the mouthpiece for limiting outward movement of the clamp subsequent to the cigarette becoming freed from said gripping fingers, said fingers being formed with flanges at their outer ends which conjointly form a continuous annulus adapted to abut the outer end of the mouthpiece to limit the inward longitudinal movement of the clamp, said annulus projecting radially

beyond the periphery of the mouthpiece to form means for manually engaging and moving the clamp outwardly toward ejecting position, and a peripheral shoulder of substantially 30° formed conjointly on said gripping fingers for engagement with the outer end of the counterbore whereby a short manually actuated initial movement of the clamp in an outward direction will be automatically followed by a further outward movement of increased rapidity to simultaneously release and thrust the cigarette bodily from the gripping fingers of the clamp.

12. In a cigarette holder, the combination of a mouthpiece formed with a bore and with a counterbore at its outer end, and a clamp positioned in said counterbore for longitudinal movements therein for alternately holding and ejecting the cigarette, said clamp being formed of a spring metal tube split longitudinally to form outwardly extending resilient gripping fingers normally tending to open radially, the outer end portion of the tube being flared to form a seat for the inner end of the cigarette and an exterior inclined shoulder adapted to cooperate with the outer end of the mouthpiece whereby a short manually controlled initial movement of the clamp in an outward direction will be automatically followed by a further outward movement of increased rapidity to simultaneously release and thrust the cigarette from the clamp.

13. In a cigarette holder, the combination of a mouth piece formed with a bore and with a counterbore at its outer end, and a clamp positioned in said counterbore for longitudinal movements therein for alternately holding and ejecting the cigarette, said clamp being formed of a spring metal tube split longitudinally to form outwardly extending resilient gripping fingers normally tending to open radially, the outer end portion of the tube being flared to form a seat for the inner end of the cigarette and an exterior inclined shoulder adapted to cooperate with the outer end of the mouthpiece whereby a short manually controlled initial movement of the clamp in an outward direction will be automatically followed by a further outward movement of increased rapidity to simultaneously release and thrust the cigarette from the clamp, the outer end of the clamp terminating in a circumferential flange forming a finger engaging portion for manually controlling said initial outward movement of the clamp, that portion of the tube between the inclined shoulder and the flange frictionally engaging the inner wall of the counterbore of the mouthpiece to retain the clamp against accidental outward movement relative to the mouthpiece.

14. In a cigarette holder, the combination
